UNITED STATES PATENT OFFICE.

HENRY R. TOWNE, OF NEW YORK, N. Y., ASSIGNOR TO THE YALE & TOWNE MANUFACTURING COMPANY, OF STAMFORD, CONNECTICUT.

DESIGN FOR A KEY.

SPECIFICATION forming part of Design No. 29,786, dated December 13, 1898.

Application filed August 24, 1898. Serial No. 689,437. Term of patent 14 years.

To all whom it may concern:

Be it known that I, HENRY R. TOWNE, a citizen of the United States, and a resident of New York, in the county and State of New York, have invented and produced a new and original Design for a Key, of which the following is a specification, reference being had to the accompanying drawings, forming a part thereof—

10 Figure I is a view of the obverse side of a key, showing my new design for the bow or handle thereof. Fig. II is a view of the reverse side of the same.

15 As shown in the drawings, the leading material feature of my design consists in the shape, form, and configuration of the bow or handle of the key, which consists of a substantially circular disk having a raised periphery or

border and a ring-opening having also a raised border, said ring-opening being eccentrically located near the periphery of the key-bow. On one side of the bow or handle there is a trefoil figure, the central foil of which surrounds the ring-opening. The other side of the bow or handle provides a large panel, which may be used for lettering or other design.

20 Having thus described my invention, the following is what I claim as new therein and desire to secure by Letters Patent:

25 The design for a key; substantially as herein shown and described.

HENRY R. TOWNE.
